Inventor:

William R. Thompson,
By his Attorney, Emerson K. Newell

UNITED STATES PATENT OFFICE.

WILLIAM R. THOMPSON, OF NORWALK, CONNECTICUT, ASSIGNOR OF ONE-HALF TO GEORGE N. MCKIBBIN, OF NORWALK, CONNECTICUT.

ELECTRIC SWITCH.

SPECIFICATION forming part of Letters Patent No. 717,724, dated January 6, 1903

Application filed May 28, 1902. Serial No. 109,263. (No model.)

2 all whom it may concern:

Be it known that I, WILLIAM R. THOMPSON, a citizen of the United States, residing at Norwalk, Connecticut, have invented certain new and useful Improvements in Electric Switches, of which the following is a clear, full, and exact description.

My invention relates to an electric switch; and my object is to improve the construction 10 of the same and at the same time to provide a switch which is simple and compact and which will insure good electrical contact between the terminals.

My invention will be defined in the claims.

15 In the drawings showing the preferred embodiment of my invention, Figure 1 shows a top plan view with a diagram of electrical connections; Fig. 2, a bottom plan view, and Fig. 3 a central vertical section of Fig. 1.

20 1 is a base of insulating material—such, for example, as hard rubber. In the bottom of the base I have formed a recess, preferably in the shape of an elongated channel.

25 2^a is a slot, preferably elongated, as shown, which extends through the base and communicates with the recess. 3 and 4 are electrical contact-terminals at either side of said slot, and 6 is a third terminal, which may be metallic plates let into depressions in the bottom of said recess, so that they are flush with the bottom of said recess, as shown in Fig. 3, and insulated from each other. 5 is a switch-

30 terminal which may be in the form of a bow-spring located in said recess with its ends pressing against the bottom of said recess and adapted to bridge either of said side terminals and the middle terminal 6. 7 is a stud attached to said spring and extending through said slot 2^a, by which said spring may be shifted

35 40 from the position shown in Fig. 1 to that shown in Figs. 2 and 3. This stud preferably has a finger piece or button 8, whose base forms a flange extending laterally beyond said slot, as shown in dotted lines in Fig. 1, for holding the spring under tension. The ends of the spring press firmly against the contact-plates, and as the spring is shifted from one position to the other they rub over the plates and insure a good electrical connection. Binding-posts or screws 9, 10, and 11 may be pro-

vided on each of the terminal plates, if desired.

As all the electrical connections are in the embodiment illustrated located above the bottom of the base, the switch may be attached to 55 any structure without danger of short-circuiting. It is also simple, compact, and efficient in its action. It is particularly useful in connection with a sparking device of an explosive-engine where it is desirable to start the engine 60 by connecting the sparking device with a battery and then switching it into circuit with a dynamo. I have illustrated such an arrangement in diagram in Fig. 1, in which 12 indicates a sparking device, 13 a battery, and 65 14 a dynamo.

I am aware that many variations from the foregoing construction may be made without departing from my invention as claimed, and I therefore do not desire to be limited to the 70 embodiment herein illustrated and described.

What I claim is—

1. In an electric switch in combination, a base of insulating material having a recess in the bottom of said base and a slot through 75 said base communicating with said recess, a metallic contact-terminal carried by said base at one side of said slot, a second contact-terminal, and a metallic spring located in said recess and adapted to bridge said terminals, 80 a projection through said slot to shift said spring.

2. In an electric switch in combination, a base of insulating material having a recess in the bottom of said base and a slot through 85 said base communicating with said recess, a metallic contact-terminal carried by said base at each side of said slot, a third contact-terminal between the same, a metallic spring located in said recess and adapted to bridge 90 either of said side terminals and said middle terminal, and a projection through said slot to shift said spring.

3. In an electric switch in combination, a base of insulating material having a recess in the bottom of said base and an elongated slot through said base communicating with said recess, a metallic contact-terminal carried by said base at each side of said slot, a third contact-terminal between the same, a 100

metallic spring slidable in said recess and adapted to bridge either of said side terminals and said middle terminal, and a projection through said slot and attached to said 5 spring to shift said spring.

4. In an electric switch in combination, a base of insulating material having a recess in the bottom of said base and an elongated slot through said base communicating with 10 said recess, a metallic contact-terminal carried by said base at each side of said slot, a third contact-terminal between the same, a metallic spring slidable in said recess and adapted to bridge either of said side terminals 15 and said middle terminal, and a projection through said slot to shift said spring, said projection being attached to said spring and having a flange projecting laterally beyond said slot to hold said spring under tension. 20
5. In an electric switch in combination, a base of insulating material having a recess

in the bottom of said base and an elongated slot through said base communicating with said recess, a metallic contact-terminal carried by said base at each side of said slot, a third contact-terminal between the same, 25 said side terminals being let into the material of said base flush with the bottom of said recess, a metallic bow-spring pressing with 30 its ends against the bottom of said recess and slidable in said recess and adapted to bridge either of said side terminals and said middle terminal, and a projection through said slot to shift said spring, said projection being attached to said spring and supplied with means for holding said spring under tension. 35

Signed at South Norwalk, Connecticut, this 16th day of April, 1902.

WILLIAM R. THOMPSON.
